UNITED STATES PATENT OFFICE

2,417,683

ELECTRIC AIR CIRCUIT BREAKER

Winton G. Harlow, Upper Darby, Pa., assignor to
 General Electric Company, a corporation of
 New York

Application April 13, 1944, Serial No. 530,912

5 Claims. (Cl. 200—147)

1

My invention relates to electric switches, and more particularly to air circuit breakers of the load-break disconnecting switch type for an intermediate voltage rating such as 15,000 volts, capable of interrupting and efficiently clearing load power circuits, and has for its principal object the provision of an improved arc chute for a circuit breaker of the aforesaid type that greatly increases the circuit interrupting ability. Specifically my invention is an improvement in electric air circuit breakers of the type disclosed in United States Letters Patent 2,399,485, issued April 30, 1946, and assigned to the same assignee as the present application.

My invention will be more fully set forth in the following description referring to the accompanying drawing, and the features of novelty which characterize my invention will be pointed out with particularity in the claims annexed to and forming a part of this specification.

Referring to the drawing, Fig. 1 is an elevational view of an air circuit breaker embodying the present invention and shown in the closed circuit position thereof; Fig. 2 is an elevational view, partly in section, of the arc chute of the circuit breaker shown in Fig. 1 embodying my invention; Fig. 3 is a sectional view taken on line 3—3 of Fig. 2; Fig. 4 is a top view, partly in section, of the arc chute of Fig. 2; Fig. 5 is a sectional view taken on line 5—5 of Fig. 2, and Fig. 6 is an exploded perspective view of the stationary arcing contact of my improved circuit breaker.

The air circuit breaker shown in Fig. 1 is adapted both to interrupt load currents (as well as low amperage magnetizing currents), and to disconnect the circuit generally in the manner of the air break disconnecting switch.

Referring now to Fig. 1, the circuit breaker comprises a pair of relatively fixed terminals indicated at 10 and 11 arranged to be interconnected in the normal closed circuit position by a main current-carrying contact member 12. The contact member 12 is formed as a double blade contact that is secured to and mounted on a rotatable insulating shaft 13 for pivotal movement with respect to the upper fixed terminal 10. An operating handle 14 is connected to the insulating shaft 13 for rotating the same and causing the contact member or blade 12 to move toward and away from the fixed terminal 10.

The upper terminal 10 has connected thereto a fixed contact structure including an arcing contact 15, best shown in Figs. 2 and 6, and main current-carrying finger-type contacts 16 ar-

1
 ranged to be engaged by the blade 12 (Fig. 1). Also mounted on the fixed terminal is an arc extinguishing structure, generally indicated in Fig. 2 at 17, comprising in the specific instance a narrow arc chute to be described in greater detail hereinafter. The arcing contact 15 is mounted within the arc chute for coaction with a movable arcing contact 18 that is pivotally mounted on and carried by the main blade as indicated at 19 (Fig. 1), whereas the main current contacts 16 are disposed exteriorly of the arc chute at opposite sides thereof as also indicated in Figs. 1 and 2.

2
 The movable arcing contact 18 is operatively related to the main current carrying blade 12 so that when the handle 14 is rotated clockwise from the position shown in Fig. 1 to open the circuit breaker, the main contacts at 12 and 16 first part contact and move a predetermined distance 15 toward open circuit position before parting of the arcing contacts occurs at 15 and 18. Since the arcing contact 18 is electrically connected to the blades 12 the circuit between the terminals will be opened at the arcing contacts rather than 20 at the main contacts so that the arc to be extinguished is drawn within the arc chute 17 where it attaches to the arcing horns and is extinguished as it moves into the baffle structure of the arc chute 17 to be described hereinafter.

25 To this end the movable arcing contact 18 is latched so that it does not immediately or completely follow the blades 12 until the blades reach a certain position whereupon the latch is tripped by means associated with the blade, and spring 30 biasing means which are stressed during the initial movement of the blade cause the movable arcing contact to snap away from its fixed contact 15. Coincident with this operation a strong jet of air is directed substantially transversely of 35 the arc stream at the arcing contact so as to drive the arc upward within the chute, thereby to facilitate the interruption of large as well as small current arcs.

30 The specific construction of the latching 45 means, spring biasing means and air jet producing means forms no part of the present invention. Preferably these elements are constructed in accordance with the disclosure in the above mentioned Letters Patent. The latching means comprises a toggle adapted to be held in the over-center position by spring means 20. The upper end of the toggle is provided with a roller 21 which is adapted to engage a fixed catch 22 provided on either side of the arc chute 17, best shown in Figs. 55 2 and 3. The spring biasing means for the arcing

contact 18 is not shown in the drawing, but preferably comprises a coiled spring or the like associated with the axis 19 about which the arcing contact 18 pivots. The air jet producing means is generally indicated at 23 and is operated upon movement of the movable arcing contact 18 away from the stationary arcing contact 15.

My invention is specifically concerned with a new and improved arc chute or arc extinguishing structure which comprises spaced side walls 24 and 25 composed of arc resisting material, such as asbestos board comprising a mixture of Portland cement and asbestos, each side wall having on the side facing the other wall a plurality of parallel fins 24' and 25', respectively, as best shown in Figs. 2 and 4. The fins 24' and 25' are preferably integral with the side walls which are joined and suitably clamped together at the ends 26 and 27. Each of the ends is preferably closed by a suitable spacer member 28. The chute sides 24 and 25 with the spacer members 28 are suitably bolted together, as indicated at 29, and preferably a sheet of insulating material 30 is provided on the outside of each side wall and also clamped by bolts 29 to give increased strength to the arc chute so that shock or vibration will not cause destruction thereof. The fixed catch 22, referred to above, is preferably formed as an integral part of each insulating sheet 30.

The arrangement and spacing of the fins 24' and 25' is such that when the side walls 24 and 25 are clamped together the fins are spaced and interleaved with respect to each other in staggered relation so as to form a sinuous or zigzag passage 31 (Fig. 4), into which the arc drawn is driven and extinguished. Preferably the fins 24' and 25' do not extend throughout the entire length of the arc chute, but the lower portion of the arc chute as viewed in Fig. 2 has no fins so as to provide a narrow slot 32 (Fig. 3) within which the arc is drawn. Preferably the fins extend along more than 50% of the surface of side walls 24 and 25.

Referring now to Fig. 3, which shows a transverse section of the zigzag arc chute passage defined by the fins 24' and 25', the fins are shown as tapered toward the entrance of the arc chute where they terminate into the portion of the chute which defines the narrow slot 32, within which the arc is initially drawn. The tapering edge is preferably defined by a curvilinear contour, as illustrated, with the angle defined by the intersection of the curved edges being an acute angle. In accordance with my invention, the fins 24' and 25' near the exhaust end of the arc chute which is the upper portion of the chute as viewed in Fig. 2, are rectangular in construction and the curvilinear portion thereof does not start until about the points 33 in Fig. 3, a substantial distance from the exhaust end of the chute such as at least one-quarter of the chute dimension. Furthermore, above points 33 the fins associated with one chute side wall abut the other chute side wall, as is clearly shown in Figs. 3 and 4. By "engage" is meant that the parts are sufficiently close so that for all practical purposes they are in actual engagement whereby with this arrangement the chute is effectively closed at the exhaust end in so far as movement of the arc into the exhaust portion of the chute is concerned. At the same time, however, the spaces 34 shown in Fig. 4 between adjacent fins 24' and 25' allow free venting of the hot arc gases. I have found that if the fins at the exhaust end of the chute are spaced from the opposite chute

side wall by less than $\frac{1}{4}$ of an inch, which spacing might be produced by manufacturing tolerances, the chute is substantially closed at the exhaust end in that it prevents the arc from being blown into this portion of the chute and in fact from travelling into the chute above the points 33 of Fig. 3, which will hereinafter be referred to as the exhaust portion of the chute. It will be seen that as the arc moves into the baffle portion of the chute the curvilinear shape of the baffles remote from the exhaust portion of the chute is such that the arc is continually lengthened and forced into intimate contact with the fins and chute sides so that it is effectively extinguished in the region between the entrance to the baffle portion of the chute and the exhaust portion of the chute, which is effectively closed in so far as movement of the arc therein is concerned.

In accordance with my invention the stationary arcing contact 15 comprises a double U-shaped member as best shown in Fig. 6, the identical portions thereof being designated as 15a and 15b, respectively, each having a downwardly extending portion one end of which is suitably fastened to a bolt 35 which supports the arcing contact in a recess 36 formed in the arc chute side walls 24 and 25. The bolt 35 electrically connects the arcing contact 15 through conductor 37 with terminal 10. Double U-shaped arcing contact also includes an upwardly extending portion 15' which is in effect a double arcing horn. The ends of this double arcing horn 15' are fastened as by welding to a pin 38 which is adapted to fit into openings 39 in chute sides 24 and 25. The arcing contact 18 is adapted to move in the space between portions 15a and 15b of arcing contact 15 which may be conveniently formed of relatively heavy wire. The arcing contact also moves in the space between the double arcing horn portion 15' of arcing contact 15.

Since the current which enters the arcing contact 15 where it is fastened to bolt 35 flows downwardly through portions 15a and 15b and then upwardly in the horn portions 15', the flux generated by the downward flow of current in portions 15a and 15b of stationary contact 15 tends to drive the arc in a downward direction which is undesirable. Accordingly I provide the portions 15a and 15b with flux shields 40 which comprise semi-cylindrical members having one end thereof welded or otherwise suitably fastened to washers 40'. These washers are adapted to be slipped over bolt 35 thereby holding the flux shields in place. The flux generated by the current flowing upwardly in the arcing horn portions 15' will therefore be the only flux affecting the arc and will cause the arc to rise to the top of the arcing horn.

In order to accommodate the flux shields 40 chute side walls 24 and 25 are provided with an additional recess 41 within recess 36.

I have provided an arcing horn 42 identical in every respect with the stationary contact in arcing horn 15, described above, for the other side of arc chute 17. This arcing horn 42 is mounted in a recess 36 identical with the recess 36 described heretofore. The stationary contact 18 is adapted to move in the space between the double U-shaped members forming arcing horn 42 so as to literally wipe the arc off from arcing contact 18 onto arcing horn 42 whereupon the jet of air from the jet producing means 23 will force the arc into the baffle portion of arc chute 17.

It should be understood that the chute side

walls 24 and 25 having the integral fins 24' and 25' respectively, might be machined from asbestos board or might be molded from a suitable asbestos compound. In the event that the chute side walls were molded two recesses 36 and 42 would be molded in each side wall whereby the two chute side walls 24 and 25 would be identical and interchangeable.

In accordance with the disclosure of Boehne Patent 2,270,723, assigned to the same assignee as the present application, the side walls of arc chute 17 defining the narrow slot 32 of Fig. 3, are given a flame treatment thereby driving the moisture out of the chute and breaking up the surface fibre structure of the material so as to prevent moisture from subsequently readily passing through the glazed surface. This flame treatment improves the dielectric qualities of the chute and acts otherwise in a useful manner. I have discovered, however, that when the current to be interrupted is low, as for example of the order of normal load, the interrupting ability and operating life are increased by omitting the flame or glazing treatment from the fins 24' and 25' in the upper portion of the arc chute. In accordance with my invention, the flame treatment, therefore, is given only in the throat portion up to a point such as is indicated by the broken line 43 in Fig. 2 although it may continue a moderate distance up the fins 24' and 25' with some reduction in effectiveness. The preferred treatment, therefore, results in an arc chute which is coated in its throat portion, with a glaze consisting of the fusion products of the chute material such as Portland cement—asbestos fusion products, but which leaves the fins 24' and 25' free to absorb moisture and give it off again, in the presence of an arc, to assist in the interruption of the arc.

From the above discussion it will be observed that I have provided a new and improved arc chute which is simple and inexpensive and which provides greatly increased circuit interrupting ability.

Although I have disclosed a particular embodiment of my invention, it will be obvious to those skilled in the art that modifications may be made without departing from my invention and I intend in the appended claims to cover all such changes and modifications as fall within the true spirit and scope of my invention.

What I claim as new and desire to secure by Letters Patent of the United States is:

1. An electric air circuit interrupter comprising relatively movable contacts between which an arc may be formed upon opening of the circuit, and an insulating arc chute into which said arc is driven comprising spaced side walls, each side wall having on its side facing the other wall a plurality of ridges extending longitudinally in the general direction of movement of said arc through said chute, the ridges of one wall being closely adjacent to, overlapping and staggered with respect to the ridges of the opposite wall so that the arc in passing through said chute is forced to take a tortuous closely confined path around the outer edges of said ridges to increase the length of and attenuate said arc, said ridges associated with each side wall at the exhaust portion of said chute abutting the other side wall so as to interrupt the continuity of said tortuous arc path at the outer edge of each ridge over a predetermined portion of the chute whereby to prevent the travel of the arc into this portion of the chute.

2. An electric air circuit interrupter comprising relatively movable contacts between which an arc may be formed upon opening of the circuit, and an insulating arc chute into which said arc is driven comprising spaced side walls, each side wall having on its side facing the other wall a plurality of ridges extending longitudinally in the general direction of movement of said arc through said chute, the ridges of one wall being closely adjacent to, overlapping and staggered with respect to the ridges of the opposite wall so that the arc in passing through said chute is forced to take a tortuous closely confined path around the outer edges of said ridges to increase the length of and attenuate said arc, said ridges associated with each side wall at the exhaust portion of said chute abutting the other side wall so as to interrupt the continuity of said tortuous arc path at the outer edge of each ridge whereby to prevent the passage of the arc past said abutting edges.

3. An electric air circuit breaker comprising relatively movable contacts between which an arc may be formed upon opening of the circuit, and an insulating arc chute into which said arc is driven comprising spaced side walls, each side wall having on its side facing the other wall a plurality of ridges extending longitudinally in the general direction of movement of said arc through said chute, the ridges of one wall being closely adjacent to, overlapping and staggered with respect to the ridges of the opposite wall so that the arc in passing through said chute is forced to take a tortuous closely confined path around the outer edges of said ridges to increase the length of and attenuate said arc, said ridges associated with each side wall at the exhaust portion of said chute abutting the other side wall so as to interrupt the continuity of said tortuous arc path at the outer edge of each ridge over a predetermined portion of the order of one quarter of the chute measured from the exhaust end of the chute whereby to prevent travel of the arc into this portion of the chute.

4. An electric circuit interrupter comprising a pair of relatively movable contacts between which an arc is drawn upon separation of said contacts, an arc chute associated with said contacts, one of said contacts being a stationary contact mounted within said arc chute, said stationary contact comprising a cylindrical rod of U-shaped configuration with the base of the U extending downwardly in said arc chute, means for supporting said contact in said arc chute at the upper end of one of the legs of said U, the other of said legs of said U forming an arcing horn, means for connecting an associated electric circuit to said contact at the upper end of said one leg, and flux shielding means for substantially enclosing said one leg of said U comprising a pair of semi-cylindrical members formed of magnetic material.

5. An electric circuit interrupter comprising a pair of relatively movable contacts between which an arc is drawn upon separation of said contacts, an insulating arc chute associated with said contacts, one of said contacts being a stationary contact mounted within said arc chute, said stationary contact comprising a heavy wire of a double U-shaped configuration with the base of the U extending downwardly in said arc chute, the other of said contacts being movable to engage both portions of said double U-shaped contact, means for supporting said contact in said arc chute at the upper end of one of the legs of said

U, the other of said legs of said U forming an arcing horn, and means for connecting an associated electric circuit to said contact at the upper end of said one leg.
